Specification for Design.

Patented Nov. 23, 1920.

Application filed November 28, 1919. Serial No. 341,316. Term of patent 14 years.

To all whom it may concern:

Be it known that I, LESTER P. WINCHEN-
BAUGH, a citizen of the United States, resid-
ing at Hyde Park, in the county of Suffolk
and State of Massachusetts, have invented
a new, original, and ornamental Design for
Ornamental Paper, Cardboard, and Similar
Articles, of which the following is a speci-
fication, reference being had to the accom-
panying drawing.

In the drawing the figure is a face view of
a portion of a sheet of paper showing the
novel design.

In applicant's novel design the paper,
where the colors are applied thereto, has a
stained or dyed appearance. The stripes of
the design have no sharp, hard edges but the
margins thereof are irregular and some-
what indistinct, and the colors blend into
each other giving a soft and pleasing effect
to the eye.

What is claimed is:

The ornamental design for ornamental
paper, cardboard or similar article as shown
and described.
